UNITED STATES PATENT OFFICE.

IRVING I. STONE, OF CHICAGO, ILLINOIS, ASSIGNOR, BY DIRECT AND MESNE ASSIGNMENTS, TO G. A. EDWARD KOHLER, OF CHICAGO, ILLINOIS.

APPARATUS FOR FEEDING PAPER TO PRINTING-PRESSES, &c.

1,124,673.

Specification of Letters Patent.

Patented Jan. 12, 1915.

Application filed June 18, 1900. Serial No. 20,682.

To all whom it may concern:

Be it known that I, IRVING I. STONE, citizen of the United States, residing at Chicago, in the county of Cook and State of Illinois, have invented a certain new and useful Improvement in Apparatus for Feeding Paper to Printing-Presses, &c., of which the following is a full, clear, concise, and exact description, reference being had to the accompanying drawing, forming a part of this specification.

My invention relates to apparatus for feeding paper to printing presses, etc., my object being to provide a suitable device adapted to hold a plurality of rolls of paper or like material adapted to be fed to printing presses or other mechanism, the support being associated with a feeding device whereby the rolls may be successively brought into engagement with the feeding device to feed the paper therefrom.

I have illustrated my invention in the accompanying drawings in which:—

Figure 1 is a view of one end of the device of my invention showing the means employed for rotating the frame. Fig. 2 is a side view of the rotating device. Fig. 3 is a view of the other end of the device of my invention showing the rolls of paper in position. Fig. 4 is a view of the belts employed to feed the paper to the press. Fig. 5 is a detail view showing one method of securing the rolls of paper when paper spools are used. Fig. 6 is a side view of my invention showing the reel partly turned in the process of changing the feed from one roll to the other. Figs. 7, 8, and 9 are diagrams showing the working of the device of my invention. Figs. 10 and 11 are views of the switch controlling the motor. Fig. 12 is a diagram of the circuit connections thereof. Fig. 13 is a view of an automatic attachment for this switch. Fig. 14 is a detail view of the springs in Fig. 13.

Like letters refer to like parts in the several figures.

An axle or shaft *a* is mounted in bearings *b* on the frame work *b*. Upon the axle *a* is carried a frame *o* consisting of a plurality of arms, *d*, of equal length, each carrying at its extremity a bearing *c* for the shaft *c* which carries the paper roll *e*. The frame *o* is rotated about the axle *a* by means of a worm *a²*, which acts upon the periphery of a worm wheel *a'*, which is keyed or other-

wise fixed to the axle *a*. The worm *a²* may be turned by either the hand wheel *a³*, for small adjustment of the rolls, or by means of a motor *a⁵* acting by means of the pinion *a⁶* driving the gear wheel *a⁴*, in order to bring another roll of paper into position to be run into the press, after the roll previously in position has been exhausted. In the construction illustrated the rolls of paper are fastened to the axle *c* by means of a device like that shown in Fig. 5, which consists of a continuation *c²* of the shaft *c* which has a slot *c³* cut therein. In this slot is pivoted, at *c⁴*, a bar *c⁵*, which has two or more teeth *c⁶*, at its outer extremity. A bolt *c⁷* is adapted to move the bar *c⁵* so that the teeth *c⁶* will engage the roll of paper, and fasten it in position. Normally the spring *c⁸* keeps the bar *c⁵* in such a position that the teeth *c⁶* are withdrawn into the slot. When it is desired to fasten a roll into place, the extension *c²* is pushed into the bore of the roll *e*. The bolt *c⁷* is then turned to swing the bar *c⁵* into such a position that the teeth *c⁶* will engage the inside of the roll and hold the paper firm. There are two shafts or spindles *c* for each roll. These spindles are in alinement and adapted to grip the bore of the roll when the roll is in position.

The belt *f* of leather or other suitable material runs on the wheels *f'* *f''*, and passes over a portion of the periphery of the roll *e* from which the paper is passing to press. The weight of the belt and its frame is sufficient to produce enough friction between the belt and the paper for the roll to be rotated by the revolution of the belt and the paper thereon fed into the press. One of the wheels *f'* rotates upon an axle *f³* which is suspended from the ceiling or other partition by a hanger *f⁴*. The other wheel *f''* rotates upon an axle *f⁹*, which is carried by the lower end of the frame *f²*, which depends from the axle *f³*. The frame *f²* is so pivoted that as the amount of paper on the roll decreases the frame descends, thus lessening the weight upon the roll in proportion as the amount of paper decreases, thus providing a substantially constant strain or tension upon the paper, which would not be obtained were there a constant weight upon the top of the roll. When it is desired to raise the belt *f* from in contact with the roll *e* the hook *f⁸* may be connected

to the bar f^5 and the chain f^7 running over the pulley f^8 tightened by admitting compressed air into the chamber g , by means of the stop-cock g^2 . Power is supplied to the wheels f' from any convenient source and the belts are driven at the proper speed to properly feed the paper to the press.

In supplying the rolls of paper to the machine they are placed upon a truck m which 10 rides upon a track m^2 by means of wheels m' . Part of this track runs upon a platform n which moves upon wheels n' . The truck containing a roll of paper is pushed upon the platform n and the platform n pushed 15 out until the center c^2 is in the circle formed by the axis c in its rotation. The frame c is then rotated by means of the motor a^5 until the axis c is in alinement with the bore c^2 . The roll e is then fastened in position as 20 described, the frame o rotated, and another roll put in. It will be noted that the truck which is used to carry the rolls of paper to the frame is in fact in two parts which may be called trucks. The paper is received 25 upon the platform or truck m , which has wheels running on rails on the part or truck n , while the truck n has wheels running on rails at right angles to the rails carried by it. When one roll has been exhausted 30 somewhat. The flaps e' on the next roll have been gummed on the outside and retained in position close to the roll by a little adhesive placed underneath them. The frame o is 35 now rotated to the position shown in Fig. 8, where the second roll comes in contact with the belt f . This contact causes the roll to rotate and the flaps e' passing between the belt f and the roll e are thereby gummed 40 to the paper running to press from the first roll. The paper on the first roll is then severed as shown at the dotted lines and the frame o rotated into position shown in Fig. 9, and the second roll run to press. This act 45 is accomplished by a mere slackening of the speed of the press causing but slight delay.

The position of the paper as it goes into the press is regulated by the margin governor k which is clamped or otherwise secured to the axle c . The position of the margin governor and consequently the position of the roll of paper is altered by means of the hand wheel k' operating the screw k^2 , which is fixedly attached to the 55 margin governor k .

When the device is in operation, the pressure between the belt f and the roll, and hence the feed, may be varied and regulated by moving the roll with relation to the belt so as to change the point of contact and bring it nearer to or farther from the pulley f^1 about which the belt f travels. This movement is obtained in any degree by moving the frame upon which the rolls are 60 mounted. Stating this in another way, this

movement varies the position of the point of contact with relation to the point of support of the belt, and I have found that by this means I am able to adjust the feed to meet the conditions presented. As the material on the roll is fed forward and the roll decreases in diameter, it is very beneficial to decrease the pressure between the belt and the material, and this result is automatically produced in the device herein shown and is 70 in fact responsive to the variation in the diameter of the roll.

In order to obtain as near as possible the exact amount of rotation for the frame o , I provide the device shown particularly in 80 Fig. 13. A plate of fiber p is screwed onto the end of the axle a . Into this plate is fitted the metal ring p' having the outwardly extending arms p^2 . Two segments of fiber p^3 p^4 are screwed upon the bearing 85 b' . To these segments are attached two copper springs p^5 p^6 . To these springs are attached the brushes p^8 p^9 , one of which rests upon the ring p' , and the other upon the segments p^9 of the fiber plate p . The 90 spring p^6 is made adjustable by fastening it movably upon the run way p^7 .

The copper strips s^6 of the switch s are adapted to fit into the terminals s' in such a way that by connecting one pair the motor a^5 will be run in one direction, and reversed by connecting the other pair. The magnets s^2 are connected in series with the motor a^5 , so that when the motor has been started the magnets will be energized and 100 hold the handle s , which is of magnetic material against the armatures s^3 , s^4 against the tension of the spring s^5 . One end of the windings on the magnets s^2 is connected 105 with the spring p^5 , and the other end with the spring p^6 .

When it is desired to rotate the frame o , to place in a new roll of paper, the switch s is moved to start the motor a^5 , which rotates the frame o . This also energizes the magnet s^2 , which holds the switch in position. As the frame rotates, the plate p and the ring p' revolve also until one of the arms p^2 strikes the brush p^8 of the spring p^6 , thus short circuiting the magnet s^2 . The spring s^5 now forces the handle out of contact with the terminals s' , and allows it to drop to its normal position, thus breaking the circuit through the motor a^5 .

In practice, the spring p^5 is adjusted so 120 that the magnet will be short circuited when the frame is in the position shown in Fig. 8. The pasting and cutting is then done, and the switch manipulated by hand to rotate the frame to the position shown in Fig. 9.

As illustrated in Fig. 1 the point of suspension of the feeding belt is in a vertical plane which passes through the roll upon which the belt is operated.

It will be noted that prior to pasting the 125

web of the new roll to the web of the old roll the two rolls are brought to substantially the same speed, and then while the webs are traveling at substantially the same speed, 5 they are pasted together. In the present instance it will be noted that this speed must necessarily be the same, because of the fact that the same belt F engages both webs and causes them to travel with it. It is of course 10 evident that any other suitable means for this purpose may be used.

It will be noted that in this construction there is always a supplemental roll with 15 means for rotating it so that its periphery will move with approximately the same speed as the web of the roll from which the paper is being fed, there being means for attaching the end of the web on the supplemental roll to the web being fed from 20 the other roll.

Having described my invention what I claim as new and desire to secure by Letters Patent is:—

1. In a paper feeding device for printing 25 presses, the combination with a frame adapted to carry a plurality of rolls of paper, of a device for frictionally engaging one of said rolls to feed the paper therefrom to the press, and means for moving the rolls successively into position to be engaged by the feeding device substantially as described.

2. In a paper feeding device for printing 35 presses, the combination with a rotatable frame adapted to carry a plurality of rolls of paper at different angular positions, of a device adapted to frictionally engage one of said rolls to feed the paper therefrom to the press, and means for rotating said frame to move the rolls successively into engagement 40 with the feeding device, substantially as described.

3. In a paper feeding device for printing 45 presses, the combination with a rotatable frame adapted to carry a plurality of rolls of paper, of a feeding device comprising a suitably supported traveling belt adapted to frictionally engage the roll, said belt being pivoted at the upper end and adapted to rest by gravity against the roll to feed the paper 50 therefrom to the press, and means for rotating said frame in a direction to carry the roll from which the paper is being fed past the free end of said feeding device and to carry the next succeeding roll into engagement 55 with said feeding device, whereby the swinging movement of the feeding device permits the rolls to be successively moved into position without interfering with the continuous operation of the feeding device, 60 substantially as described.

4. The combination of a movable frame 65 with a series of rolls of paper or the like mounted thereon, a frictional feeding device adapted to engage the material on one of the rolls so as to feed it forward, means for

moving said frame so as to successively bring the several rolls in operative relation with the frictional feeding device, and means for automatically changing the feed from one roll to the other. 70

5. The combination with a movable frame carrying a series of rolls of paper or the like of a feeding device which engages the paper before it leaves the roll and adapted to feed the paper forward to the press, and 75 means for automatically changing the feed from one roll to the other.

6. The combination with a frame carrying a plurality of rolls of paper or the like, of a feeding device adapted to engage one 80 of said rolls to feed the paper therefrom, said feeding device being suspended at the upper end and so mounted that when the roll is full it will rest at an angle with the vertical and will be adapted as the paper is 85 fed from the roll to more nearly approach the vertical, and means for moving said rolls successively into engagement with said feeding device, substantially as described.

7. In a paper feeding device for printing 90 presses, the combination with a frame adapted to carry a plurality of rolls of paper of a device for feeding the paper therefrom to the printing press, said device mounted so as to be free to move to and from said rolls, 95 and means for moving the rolls successively into position to be acted upon by the feeding device.

8. The combination with a frame and a suitable spindle for supporting a roll of 100 paper or the like of two separated bearings for said spindle permitting the rotation and the longitudinal movement of the spindle therein, and a margin governor for adjusting said spindle longitudinally comprising 105 a screw k^2 , a stationary bearing therefor, and a part adapted to be moved thereby mounted upon said spindle between its bearings, substantially as described.

9. A paper feeding device for successively 110 feeding paper from two rolls of paper comprising a feeding device for feeding the paper from one of said rolls, the other roll being normally out of engagement with said feeding device and having its extremity 115 suitably gummed or provided with an adhesive, and means for moving the latter mentioned roll into engagement with the feeding device in such a manner that the gummed extremity thereon will be forcibly 120 pressed against the paper proceeding from said first mentioned roll, whereby the paper will be fed from said second mentioned roll without manual pasting, substantially as described. 125

10. The combination with a supporting apparatus for a pair of rolls of paper or similar material, of means for feeding the paper from one of said rolls, the other roll being normally idle and having its extrem- 130

ity suitably gummed or provided with an adhesive, and means for moving said latter mentioned roll so that the gummed extremity thereof will be forcibly pressed against the paper proceeding from said first mentioned roll, whereby the paper will be fed from said latter mentioned roll without manual pasting, substantially as described.

11. The combination with a rotating frame carrying a plurality of rolls of paper or the like of a feeding device adapted to engage one of said rolls to feed the paper therefrom, the other roll being normally out of engagement with said feeding device and having a gummed or adherent extremity, and means for rotating said frame to carry the second roll into engagement with the feeding device and to forcibly press the gummed extremity thereof against the paper proceeding from said first mentioned roll, whereby the paper will be fed from said second mentioned roll without manual pasting, substantially as described.

12. The combination with a rotating frame carrying a plurality of rolls of paper, or the like, a swinging feeding device pivoted at the upper end and adapted to engage one of said rolls to feed the paper therefrom, the other roll being normally out of engagement with said feeding device and having a gummed or adherent extremity, and means for rotating said frame to carrying the second roll into engagement with the feeding device and to forcibly press the gummed extremity against the paper proceeding from said first roll, the swinging of said feeding device accommodating the movement of the rolls, substantially as described.

13. The combination with a roll carrying frame, of means for rotating said frame and a device actuated by the movement of said frame for automatically stopping the motion of said frame, substantially as described.

14. The combination with a roll carrying frame, of an electric motor for rotating said frame, and a device actuated by the movement of said frame for automatically stopping said motor, substantially as described.

15. The combination with a roll carrying frame, of an electric motor for rotating said frame, a switch for controlling said motor, a magnet adapted, when energized, to hold said switch in the closed position, and a device operated by the motion of said frame for deenergizing said magnet, substantially as described.

16. The combination with a roll carrying frame, of an electric motor for rotating said frame, a switch for controlling said motor, a magnet adapted when energized to hold said switch in the closed position, and a device operated by the motion of said

frame for short circuiting said magnet, substantially as described.

17. The combination with a supporting device carrying a roll of paper or the like of a frictional feeding contact device, which makes contact with the material on the roll so as to feed it forward and means for moving the said roll with relation to the feeding device so as to vary the pressure between them and thus adjust or control the feed.

18. The combination with a supporting device carrying a roll of paper or the like of a feeding belt adapted to engage the material on the roll and feed it forward, and means for varying the position of the roll with relation to the belt so as to adjust or regulate the feed.

19. The combination with a supporting device carrying a roll of paper or the like of a feeding frictional belt suspended near one end and engaging the material on the roll so as to feed it forward, and means for moving said roll toward and from the point of suspension of the belt so as to vary the point of contact to adjust or regulate the feed.

20. The combination with a movable frame carrying a series of rolls of paper or the like mounted thereon, a frictional feeding device adapted to engage the material on one of the rolls so as to feed it forward, and means for moving said frame so as to successively bring the several rolls in operative relation with the frictional feeding device.

21. The combination with a movable frame carrying a series of rolls of paper or the like mounted thereon, a frictional feeding belt suspended at or near one end and adapted to be brought successively into engagement with said rolls to feed the material forward, the point of suspension of said belt being in a vertical plane which passes through the roll upon which the belt is operating.

22. The combination of a movable frame carrying a series of rolls of paper or the like mounted thereon with a frictional feeding belt suspended at or near one end and adapted to be brought successively into engagement with said rolls to feed the material forward, the point of suspension of said belt being in a vertical plane which passes through the roll upon which the belt is operating and means for varying the position in any given roll with relation to the belt so as to adjust or regulate the feed.

23. The combination with a movably mounted feeding device of roll supporting devices adapted to support rolls of paper, means for moving the roll supporting devices so as to change the feed from one roll to the other, the feeding device during this movement following up one roll until it is disengaged therefrom by the other roll.

24. The combination with a movably mounted feeding device of roll supporting devices adapted to support rolls of paper, means for moving the roll supporting devices so as to change the feed from one roll to the other, the feeding device during this movement following up one roll until it is disengaged therefrom by the other roll, said latter roll having its extremity provided 5 with an adhesive arranged so as to be pressed against the paper from the other roll during the process of changing the feed from one to the other so as to be fastened thereto.

25. The combination with a carrying and 15 supporting apparatus for a plurality of rolls of paper or the like of a common driving device for setting two rolls in motion so that they will be rotating simultaneously and then pressing the paper of the two rolls 20 together while both rolls are in motion so that when adhesive material has previously been applied to the paper of one roll the paper of the two rolls will be pasted together.

26. A device for changing the feed of 25 paper to a printing press or the like from one web of paper to another comprising a common engaging device for moving both webs at substantially the same speed prior to bringing the adhesive end of the new web 30 into contact with the web being fed, and then pressing one web to the other while they are moving at this speed to cause them to unite.

27. The combination with a roll carrying 35 support for a pair of rolls of paper or the like of a feeding device for engaging the paper on one roll so as to feed it to the press, the end of the paper on the other roll being provided with adhesive material, means for 40 starting said latter roll in motion and then bringing the end with adhesive material into contact with the paper passing from the first mentioned roll and pressing it between such paper and the roll from which it is passing 45 so it will be carried along by the paper passing to the press.

28. The combination with a supporting apparatus for two rolls of paper or the like of an engaging driving device for causing 50 the rolls to be moved at substantially the same peripheral speed prior to bringing the adhesive portion of the new roll into contact with the web of the roll being fed and then when moving substantially at the same 55 speed bringing the paper of the two rolls together so as to unite the adhesive portion of one roll to the paper of the other roll.

29. A device for changing the feed of 60 paper to a printing press or the like from one web of paper to another, comprising two parts about which the two separate webs are wound, a common engaging device for simultaneously setting the two parts in motion while the portions of the two webs to be 65 united together are separated, and then

pressing together the portions of the two webs to be united while they are in motion, the portions of said webs thus pressed together being provided with uniting means.

30. The combination with a supporting 70 apparatus for a plurality of rolls of paper or the like of a device for successively moving said rolls into operative position, and a common means for setting two of said rolls in motion so that they will be rotating 75 simultaneously, and then pressing the paper of the two rolls together while both rolls are in motion so that adhesive material applied to the paper will cause the paper of the two rolls to adhere. 39

31. The combination with a supporting apparatus for a plurality of rolls of paper or the like of a device for successively moving said rolls into operative position, and a common means for setting two of said rolls 35 in motion so that they will be rotating simultaneously, and then pressing the paper of the two rolls together while both rolls are in motion so that adhesive material applied to the paper will cause the paper of the two rolls to adhere, the movement of a roll to its operative position bringing it into operative relation with the means for setting it in motion. 39

32. The combination with a supporting 95 apparatus for two rolls of paper or the like, one of which has an adhesive portion of means for fastening the webs of the two rolls together while in motion and prior to unwinding the paper from the new roll, with 100 means for moving the new roll into the position occupied by the old roll while the paper is being fed from the new roll. 100

33. In a web feeding mechanism for printing presses and the like, the combination with means for supporting an active roll and a substitute roll, of means for imparting to the substitute roll a peripheral speed substantially equal to that of the active roll prior to unwinding the substitute roll. 110

34. In a web feeding mechanism for printing presses and the like, the combination with means for supporting an active roll and a substitute roll, of means for imparting to the substitute roll a peripheral speed substantially equal to that of the active roll and pressing the webs of the two rolls together prior to unwinding the substitute roll. 115

35. In a web feeding mechanism for printing presses and the like, the combination with means for supporting an active roll and a substitute roll of a frictional device for engaging and operating either of said rolls, said device being adapted to simultaneously operate both rolls under predetermined 120 conditions.

36. In a web feeding mechanism for printing presses and the like, the combination with means for supporting an active roll and a substitute roll of a frictional device for 130

engaging and operating either of said rolls, said device being adapted to simultaneously operate both rolls and press the web of the active roll against the periphery of the substitute roll.

37. In a web feeding mechanism for printing presses and the like, the combination with a frictional feeding device, of a support for a plurality of rolls operable to move the same against said feeding device successively and against the moving web of the preceding roll, said moving web passing between the frictional feeding device and the succeeding roll.

38. In a web feeding mechanism for printing presses and the like, a traveling member disposed on one side of the web being fed into the press and means for supporting a substitute roll on the opposite side of the web, said roll being bodily movable against said moving web and said traveling member.

39. A feeding device for printing press rolls comprising a member pivoted at one end in substantially vertical alinement with the axis of the roll, the other end of said member being free, and a power driven part carried by said member to frictionally engage the roll, said member automatically moving toward a vertical position as the size of the roll decreases whereby the pressure of said member on the roll is inherently varied.

40. In a printing press, having a web roll about to expire, and a substitute roll, of means for bringing the webs of the two rolls into contact at a point on the periphery of the substitute roll, whereby the two webs may be united by an adhesive provided on one of the same.

41. In a printing press, having a web roll about to expire, and a substitute roll of means for bringing the web of the expiring roll into contact with the periphery of the

substitute roll, whereby the webs of the two rolls may be united by an adhesive on one of them, said substitute roll being revolved prior to the uniting of the two webs.

42. In a printing press, having a roll about to expire, and a substitute roll, of means for moving the substitute roll bodily against the moving web of the expiring roll, whereby the webs of the two rolls may be united by an adhesive on one of the same.

43. In a printing press, having a roll about to expire, and a substitute roll, of means for moving the substitute roll bodily against the moving web of the expiring roll, whereby the webs of the two rolls may be united by an adhesive on one of the same, and means for rotating said substitute roll prior to uniting the webs of the two rolls.

44. The combination in a feeding device for successively feeding from two rolls of paper or the like, of means for moving one roll into contact with the web of the other to unite the same and for moving the new roll into the position occupied by the old roll without interrupting the feed of the paper.

45. The combination with means for supporting a roll of paper and feeding it to the point of use, of a support for a supplemental roll of paper, and means for rotating the supplemental roll to cause its periphery to move with approximately the speed of the web being fed, and for attaching the adhesive end of the web of the supplemental roll to the web of the other roll without arresting the motion of either web.

In witness whereof, I have hereunto subscribed my name in the presence of two witnesses.

IRVING I. STONE.
